ELECTRIC SWITCH

Rudolph W. Strobel, Stephentown, N. Y., assignor
to General Electric Company, a corporation of
New York

Application May 1, 1940, Serial No. 332,718

16 Claims. (Cl. 200—114)

The present invention relates to electric switches, with reference more particularly to improvements in construction of switches designed primarily for outdoor installation.

Among the objects of the invention are the provision of an improved form of fused disconnect switch of the open drop-out type, an improved contact construction and arrangement for electric switches, and improved housing and shielding means for protecting outdoor switch contacts from weather and other adverse conditions.

Other objects and details of that which I consider to be novel and my present invention, will become apparent from the following description and the appended claims, taken in conjunction with the accompanying drawings, wherein are illustrated two exemplary drop-out, open type, fuse cutouts embodying the invention.

In the drawings, Fig. 1 is a side elevation of one of the exemplary cutouts; Fig. 2 is an enlarged side elevation, partially in section, showing details of the upper terminal parts of the cutout of Fig. 1; Fig. 3 is a sectional plan view along the line 3—3 of Fig. 2; Fig. 4 is an enlarged side elevation, partially in section, showing details of the lower terminal parts of the cutout of Fig. 1; Fig. 5 is a sectional plan view along the line 5—5 of Fig. 4, looking in the direction of the arrows; Fig. 6 is a front elevation of the lower terminal parts of Fig. 4, with some of the parts shown in section; and Fig. 7 shows a side elevation, partially in section, of a modification of the cutout of Fig. 1.

The cutout illustrated in Figs. 1-6, includes a supporting insulator 10 provided with a mounting bracket partially shown at 11. Terminal pieces 12 and 13 are cemented or otherwise rigidly secured respectively on the upper and lower ends of the insulator. These terminal pieces are in the form of relatively heavy bronze castings, but may be made of other suitable form and material which will provide the desired strength and rigidity. Each terminal piece has an integral eyeleted projection 14 to which a line conductor may be connected.

Upper terminal piece 12 has a forwardly projecting arm 15 which is of T-shaped cross-section, and on the outer end of which arm is a hood 16. In the exemplary cutout illustrated, hood 16 is an integral part of the terminal piece casting, but it may comprise a separate part attached to the terminal piece. The hood has an open front and bottom and is formed, adjacent the front, with a groove or seat 17 for a purpose 55

to be described. This seat extends approximately in a vertical plane, and portions of the side and top walls of the hood extend forwardly from the seat and flare outwardly as shown in Figs. 2 and 3, to serve as guides. The forwardly extending top wall portion also overhangs and serves as a protection for the front of the hood. A generally U-shaped latching clip 20 and two contact fingers 21 are attached to the rear inner wall of the hood. The resilient arms of clip 20 extend toward the front of the hood and are provided adjacent their ends with detent portions 22 and flaring guide portions 23. The forwardly extending contact fingers 21 are backed on their upper sides by spring strips 24 and are arranged to press generally downwardly and outwardly on a fuse holder contact as described hereinafter.

Lower terminal piece 13 also has a mounting portion of T-shaped cross-section, indicated at 25, and a forwardly extending portion formed to provide a hood 26 which is closed on the top, rear, and sides. The major portion of the bottom of this hood is closed by a removable plate 27 held in place by a screw 28. A cross-piece 29 bridges the bottom of the hood just forwardly of plate 27 and inwardly of the front of the hood. Two hook-like supports 30 extend forwardly from the cross-piece and provide trunnion seats 31 in spaced apart horizontal alignment. Hooks 30 are arranged so as to leave spaces 32 between the outwardly facing surfaces of the hooks and the adjacent opposed side wall portions of the hood, which wall portions are formed to provide disk-like bearing or guiding surface extending substantially in planes normal to the intended pivotal axis of the switch element later described. Within hood 26 and attached to the rear wall thereof is a generally U-shaped contact clip 33, the outer ends of which are bent inwardly and rearwardly to form a V-shaped contact seat 34, as shown in Fig. 5.

The lower terminal piece 13 serves as a support for a pivoted switch element or blade which in the illustrated embodiment includes a fuse holder 35 and a hinge member 36. The fuse holder comprises an insulating expulsion tube 37 which is open at its lower end and closed at its upper end by a removable cap 38. One end of hinge member 36 is pivotally attached, by a screw 40 or other suitable means, to a collar 41 rigidly secured adjacent the lower end of fuse tube 37. Intermediate the ends of the hinge member are trunnions 42 engageable with trunnion seats 31 for pivotally supporting the switch

element. On one side of the hinge member there is formed an eyelet handle 58 engageable by a switch hook, when the fuse holder is in a downwardly hanging position as illustrated in broken lines in Fig. 1, for manipulation of the hinge member into and out of engagement with trunnion seats 34. The hinge member normally is held in rigid relation to the fuse holder by a fuse link cable extension 48 which extends from the open lower end of tube 37 and is anchored to the hinge member by a clamping device indicated at 44. The fuse link, of which cable 48 is an extension, may be of any suitable form and is anchored in the upper end of the fuse holder in any suitable manner. A foot 45, formed integrally with the hinge member, is arranged to bear against the lower end of the fuse tube when the hinge member is held by the fuse link in the manner shown. A wedge-shaped contact nose-piece 46, also formed integrally with the hinge member, is arranged to project into the front of hood 26 and to engage the contact seat 34 of clip 28 when the switch element is in the closed circuit position, illustrated in full lines on the drawing. On the top of the hinge member, there is formed a transverse barrier or shield 47 which, in cooperation with hood 26 and other portions of the hinge member structure, serves effectively to house the lower contact parts against weather and other adverse conditions when the switch element is in closed position.

As previously indicated, hinge member 36 is adapted to be manipulated into position for engagement of trunnions 42 with hooks 38, by means of a switch hook engaged with handle 39. Under such conditions, with fuse holder 36 hanging in an inverted position, it is practically impossible to mount the switch element improperly. One important reason for this advantageous feature is that nose-piece 46 will engage cross-piece 29 and prevent movement of trunnions 42 into seats 34 if the fuse holder and hinge member are hanging in a position reversed from the proper position indicated in broken lines in Fig. 1.

As a further aid to proper and easy installation and manipulation of the switch element, disk-like enlargements 48 are formed respectively on the ends of trunnions 42. These disks are of substantially larger diameter than the trunnions, and the oppositely facing surfaces of the disks extend substantially in planes normal to the pivotal axis of the trunnions. The disks help to guide the hinge member into hood 26 and into proper position for engagement of the trunnions with seats 34. Also, as the switch element is swung about its pivots from the depending open position to the closed position, the disks tend to prevent any loose lateral movement of the switch element and constrain the switch element to swing along a predetermined plane normal to the intended pivotal axis of the switch element. This is due to the fact that the disks are confined in spaces 32 with the guide surfaces of the disks maintained in closely opposed relation to the adjacent guide surfaces on the side walls of hood 26.

On the upper end of fuse tube 37 is mounted a terminal ferrule 50 which is provided with a contact nose-piece 51 arranged to engage the underneath sides of spring-backed contact fingers 21 when the switch element is moved into closed circuit position. Nose-piece 51 is intended to serve not only as a current transfer part but also as a guide. To this end it is formed in the shape of a wedge or V, with the apex extending forwardly in the direction of circuit closing move-

ment of the switch element. Thus, either one side or the other of the nose-piece will strike against one of the front edges of hood 16 and thereby guide the upper end of fuse holder 36 into the hood. This insures proper engagement of the fuse holder with contact fingers 21 and latching clip 28, which clip engages cap 38 to hold the fuse holder in closed circuit position.

Upper fuse holder terminal 56 also has two arms or brackets 52 which are disposed in spaced alignment and serve as supports for a pivot pin 53. A closure device or shield 54 is pivotally supported on pin 53 for angular movement relative to the fuse holder about an axis normal to the plane of swinging of the fuse holder. Shield 54 is generally L-shaped, with one plate-like portion 56 arranged to extend approximately parallel with the upper end of the fuse holder and another plate-like portion 58 arranged to extend laterally in closely surrounding relation to the fuse holder. Portion 56 of the shield has an opening 57 through which tube 37 passes and which is of sufficient size to permit limited movement of the shield relative to the tube. Shield 54 also has an integrally formed eyelet handle 58 engageable by a switch hook or like switch operating tool for manipulation of the fuse holder into and out of closed circuit position. During movement of the fuse holder into closed position, and when it reaches the partially closed position indicated in broken lines in Fig. 2, the upper edge of plate-like portion 56 of the shield strikes against the upper part of the seat 17 in hood 16. Subsequent movement of the fuse holder into closed position then causes the plate-like portion 58 of the shield to swing upwardly from the position indicated in broken lines in Fig. 2. When the upper end of the fuse holder reaches its completely closed position, portion 56 of the shield is accommodated in a flanged seat 59 and closes the bottom of hood 16. At the same time, portion 58 of the shield is accommodated in seat 17 and closes the front of the hood. Thus, when the switch element is in closed circuit position, the upper contact parts are completely enclosed in a relatively tight housing formed by hood 16 and shield 54.

If, during operation of the cutout, shield 54 should become sleeted over or otherwise frozen to hood 16, the ice may be readily broken away and the shield freed by an upwardly directed tap on handle 58. This is due to the fact that the shield is loosely or pivotally supported for movement relative to the fuse holder, so that an upward force on handle 58 produces a leverage which readily breaks any ice formation around the edges of the shield.

On the other hand, if the fuse link in holder 36 ruptures due to overload or short-circuit, fuse link extension 48 releases hinge member 36 for movement of the latter relative to the fuse holder. This permits movement of the lower end of the fuse holder outwardly and downwardly under the influence of gravity and the downward force exerted by the spring-backed fingers 21, until the upper end of the fuse holder becomes disengaged from latching clip 28. The holder then swings in a well known manner to the dropped-out position indicated in broken lines in Fig. 1.

The general form and arrangement of parts, and the operation, of the embodiment shown in Fig. 7, are substantially the same as previously described in connection with Figs. 1-6. Hence, a detailed description will be given only of certain structural modifications, included in the embodi-

ment of Fig. 7, which are particularly advantageous for employment where a switch or cutout of exceptional ruggedness is desired. In open cut outs of the general type illustrated, it has been the common practice to construct the upper and lower switch element supports of a material of high electric conductivity, such as copper or bronze, so that at least part of such supports may be included in the electric circuit. However, with the nonferrous metals commonly employed for the purpose, there are limits to the strength which can be secured without resort to impractical dimensions or costly designs. In the construction of Fig. 7, a considerable increase in ruggedness is secured, without resort to the expedients above referred to, by the employment of switch element supports in the form of malleable iron castings. Such castings surpass, in strength and rigidity, the nonferrous castings or similar supports heretofore employed, while at the same time being easier to manufacture and substantially less expensive. In order to avoid inclusion of the malleable iron, which has relatively poor electric conductivity, in the electric circuit, I provide an improved construction and arrangement of parts such that the malleable iron castings serve only as a supporting framework while paths of good conductivity are provided for the electric circuit.

By reference to Fig. 7, it will be seen that the malleable iron casting, which forms the upper support 60, is clamped at one end to the upper end of insulator 10 by means of a U-shaped bolt 61 and cooperative clamping nuts 62. The outer end of part 60 has an integrally formed hood 63 which is similar to the hood 16 of the first described embodiment. Secured to the inner rear wall of hood 63, by means of bolts 64, is a terminal assembly including the contact fingers 21 and a terminal plate 65, which fingers and plate are comprised of material having good electric conductivity, such as copper or bronze. Spring strips 24 for backing the contact fingers, also form part of the terminal assembly. Plate 65 is provided with a socket 66 and one or more clamping screws 67 for connection of line conductors or leads thereto. Entrance openings 68, one of which is shown in the drawings, are formed in the side walls of the hood for accommodation of the line conductors or leads. Overhanging ledges 69 are formed above the entrance openings on the outer faces of the side walls of the hood so as to deflect water away from the openings.

The lower supporting part 70, which also comprises a malleable iron casting, is cemented or otherwise secured at one end to the lower end of insulator 10 and has an integrally formed hood portion 71 which is similar to the hood portion 26 of terminal piece 13 of the first described embodiment. A contact 33, similar in form to that shown in Fig. 5, is secured to the inner rear wall of hood 71 by means of bolts 72, with one end of a terminal plate 73 clamped between the contact and the rear wall of the hood. Both contact 33 and plate 73 are comprised of metal having good electric conductivity, such as copper or bronze. The terminal plate is bent into generally L-shape and the free end of the plate, disposed outside of hood 71, is provided with a socket 74 and one or more clamping screws 75 for connecting line conductors or leads thereto.

As a result of the structural improvements just described, there is secured a high degree of strength and rigidity which could not be secured with previous constructions in which the commonly employed materials of good conductivity

were used for the switch element supports. The increased ruggedness is an important advantage since it renders the cutout capable of withstanding, without damage or impairment of operation, a greater amount of rough handling and shocks incident to transportation, installation, and manual operation, as well as shocks due to powerful recoil of the expulsion tube. Also, the increased ruggedness is secured with no reduction in current carrying efficiency or convenience of making connections.

Both of the illustrated constructions are simple and economical to manufacture, and have all the advantages of an open-type switch or cutout with the additional advantage that both the upper and lower contact parts are housed so as to be effectively protected against rain, sleet, and snow under all operating conditions. The enclosing of the contact parts in the manner shown, also prevents insects from nesting under the hoods and hampers the circulation of dust-laden or corrosive atmosphere around the contact parts. Yet, neither the automatic nor the manual operation of the cutouts is in any way hindered.

The present invention is not limited in all its aspects to the particular structural details or form of the switching devices herein described and illustrated, and it is contemplated that the teachings set forth herein will suggest other modifications and applications to those skilled in the art. Hence, it is to be understood that it is intended to cover by the appended claims such other modifications and applications as do not depart from the true spirit and scope of the invention.

What I claim as new and desire to secure by Letters Patent of the United States is:

1. An electric switch of the open type, comprising spaced terminals, a protective hood for a contact portion of one of said terminals, the other of the terminals being outside of said hood, a switch element for removable connection between said terminals, said element being pivotally supported exteriorly of said hood and having a contact portion for engagement with said contact portion of said one terminal, and closure means for said hood, which said means is supported on said switch element and is formed and arranged for cooperation with the hood to provide a relatively tight housing completely enclosing said contact portion of said one terminal and said contact portion of said switch element when the latter is in connected position.

2. In an electric switch, spaced terminals, a protective hood for a contact portion of one of said terminals, the other terminal being outside of said hood, a switch element pivotally supported exteriorly of said hood and swingable into a position connected between said other terminal and said contact portion of said one terminal, and closure means for said hood including a member supported on said switch element and having a portion disposed in generally laterally extending relation to the switch element intermediate the ends of said element, which said portion of said member is arranged to form a closing wall for said hood in closely surrounding relation to the switch element when the latter is in connected position.

3. In an electric switch of the open type, a protective hood, a terminal having contact means in said hood, a switch element pivotally supported outside of and generally below said hood, the hood being open generally downwardly and to one side so as to permit swinging of a contact

portion of said switch element into engagement with said contact means, and means supported on the switch element operative to close said hood when the switch element is in connected position, said last means including a closure element extending in closely surrounding relation to the switch element intermediate the ends of said element and having a portion arranged to close the bottom part of the hood.

4. In an electric switch, spaced terminals, a protective hood for a contact portion of one of said terminals, the other terminal being outside of said hood, a switch element pivotally supported for removable connection between said other terminal and said contact portion of said one terminal, said hood having an open portion arranged to permit swinging of said switch element into connected position, and means supported on said switch element for closing said open portion of the hood when the switch element is in connected position, said means including a member disposed in generally laterally extending relation to the switch element intermediate the ends of said element and arranged to form a closing wall for the hood around the switch element, said member having an opening through which the switch element extends and being movable relative to the switch element.

5. In an electric switch of the open type, a protective hood having an open side and bottom, a terminal having contact means in said hood, a switch element pivotally supported generally below said hood and having a contact portion swingable into engagement with said contact means, and a closure device supported on said switch element and formed and arranged to close said open side and bottom of the hood when the switch element is in closed circuit position, said device having an opening through which the switch element extends and being movable relative to the switch element.

6. In an electric switch of the open type, a protective hood open on the bottom and one side, a terminal having contact means in said hood, a switch element pivotally supported generally below said hood and having a contact portion swingable into engagement with said contact means, and closure means for said hood, supported on said switch element and including two angularly related closure elements arranged to close said side and bottom, respectively, of the hood when the switch element is in closed circuit position.

7. In an electric switch, spaced terminals, a hood relatively permanently associated with and partially enclosing a contact portion of one of said terminals, the other of the terminals being outside of said hood, a switch element for removable connection between said terminals, said element being pivotally supported exteriorly of said hood and having a contact portion swingable through an open side of the hood into engagement with said contact portion of said one terminal, and means supported on said switch element for closing said hood when the switch element is in connected position, said means including two angularly related closure elements, one of which closure elements is arranged to close said open side of the hood, the other of said closure elements being arranged to close a part of the hood which is open in a direction generally toward the pivotal support of the switch element.

8. An electric switch comprising a housing structure, a terminal having contact means in

said structure, a second terminal outside of said structure, a switch element for removable connection between said second terminal and said contact means, said element having a contact portion movable generally laterally through an open side of said structure into engagement with said contact means, and a closure device supported on said switch element for closing said housing structure when the switch element is in connected position, said device being movable relative to the switch element and having two angularly related parts, one of which parts is arranged to close said open side of the housing structure, the other of said parts extending generally laterally relative to the switch element at a point intermediate the ends of said element and being arranged to close a portion of said housing structure which opens in a direction generally along the longitudinal axis of the connected position of the switch element.

9. In an electric switch, a protective hood having an open side and bottom, a terminal having contact means in said hood, a switch element pivotally supported generally below said hood and having a contact portion swingable into engagement with said contact means, and a closure device supported on said switch element and including two angularly related members arranged to close said open side and bottom, respectively, of the hood when said switch element is in closed circuit position, said device being supported for angular movement relative to the switch element about an axis generally normal to the plane of swinging movement of the switch element.

10. In an electric switch, a terminal, a housing structure relatively permanently associated with and partially enclosing a contact portion of said terminal, a second terminal located exteriorly of said housing structure in spaced relation to said first mentioned terminal, a pivoted switch element for removable connection between said terminals, said element being swingable relative to said housing structure and having a contact portion engageable with said contact portion of said first terminal, and a closure device supported on said switch element for closing an open portion of said housing structure when the switch element is in connected position, said closure device and switch element being connected for movement relative to each other and the closure device having a handle for engagement by a switch operating tool.

11. In an electric switch, spaced terminals, a protective hood for a contact portion of one of said terminals, a pivoted switch element swingable into a position connected between the other of said terminals and said contact portion of said one terminal, and guide means including a generally V-shaped part carried by said switch element and having its apex forwardly in the direction of circuit closing movement of the switch element, which said part is arranged to engage said hood in a manner to guide the switch element into connected position.

12. In an electric switch, the combination of a protective hood having an opening in one side thereof, a terminal having contact means in said hood, and a pivoted switch element having a terminal portion swingable through said opening for cooperation with said contact means in the hood, said terminal portion of the switch element including a generally V-shaped contact part disposed with its apex forwardly in the direction of circuit closing movement of the

switch element, said part being arranged to engage said hood adjacent said opening so as to guide said terminal portion of the switch element into the hood.

13. In an electric switch, a relatively stationary structure including a housing and a pair of trunnion supports disposed between and in alignment with two spaced opposed wall portions of said housing, contact means in said housing, a switch element for cooperation with said contact means and having a pair of trunnions removably engaged with trunnion seats provided by said supports for pivotally supporting the switch element, and disk-like enlargements on the outer ends respectively of said trunnions and rotatable in spaces provided between said supports and the respectively adjacent ones of said wall portions of the housing, said enlargements having guide surfaces arranged to cooperate with said wall portions of the housing so as to guide the movement of said switch element.

14. In an electric switch, a relatively stationary structure including trunnion supports, a switch element having trunnions removably engaged with said supports for pivotally supporting the switch element, said element also having disk-like guide members rigidly related to said trunnions and spaced apart substantial distances axially relative to the axis of the trunnions, said members extending in parallel relationship substantially normal to the pivotal axis of the switch element and the outer peripheries of said members being at substantially greater radial distances from said axis than the radial distance from the axis to the peripheries of said trunnions, and separate guide means forming part of said stationary structure and arranged for cooperation with said members to guide the movement of said switch element.

15. In an electric switch, relatively stationary trunnion supporting means, a switch element having a hinge part including trunnions removably engageable with said supporting means for pivotally supporting the switch element, said hinge part also including a disk-like guide member rigidly related to said trunnions and extending substantially normal to the pivotal axis of the trunnions, the outer periphery of said member being at a substantially greater radial distance from said axis than the radial distance from the axis to the periphery of the trunnions, and separate relatively stationary guide means adjacent said supporting means and arranged for cooperation with said guide member to limit angular movement of said member and trunnions to substantially pure rotation about the pivotal axis of the trunnions.
16. In an electric switch, stationary supporting means, a switch element having trunnions removably engaged with said supporting means for pivotally supporting the switch element, guide means on the switch element adjacent and rigidly related to said trunnions, said guide means having at least two bearing surfaces which face in opposite directions and extend substantially in planes normal to the axis of said trunnions, said surfaces being spaced apart a substantial distance axially relative to the axis of the trunnions and portions of said surfaces being at substantial distances radially outward from said axis, and separate means providing spaced apart oppositely facing stationary bearing surfaces respectively opposed to said first mentioned surfaces in a manner to confine said trunnions against axial movement and to limit angular movement of the trunnions to substantially pure rotation about their axis.

RUDOLPH W. STROBEL.
